ATTORNEY

UNITED STATES PATENT OFFICE.

CHARLES M. SEARS, OF LENOX, MASSACHUSETTS.

PROTECTIVE CURTAIN.

1,247,579.

Specification of Letters Patent. Patented Nov. 20, 1917.

Application filed July 10, 1917. Serial No. 179,777.

To all whom it may concern:

Be it known that I, CHARLES M. SEARS, a citizen of the United States, residing at Lenox, in the county of Berkshire and State of Massachusetts, have invented new and useful Improvements in Protective Curtains, of which the following is a specification.

This invention relates to devices for protecting the cashiers of banks and other institutions against robbers and highwaymen and it has particular reference to that class of devices in which a heavy curtain may be quickly interposed, by action of the cashier, between him and the prospective robber.

One object of the invention is to produce in a simple and improved form, a curtain which may be unrolled by gravity and which, while not in use, is retained in rolled-up condition by retaining mechanism which may be quickly and efficiently actuated to release the curtain so as to permit the same to drop.

A further object of the invention is to produce simple and improved mechanism whereby the release of the curtain also actuates a device whereby an electrical circuit is completed, the same including a bell or sounder which may be located at any desired point.

A further object of the invention is to produce a simple and improved mechanism whereby the cashier may quickly and effectively break the circuit including the bell or sounder so that, in the event of false alarm or for any other reason, such bell may be disconnected very quickly and without causing unnecessary alarm.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawings;—

Figure 1 is a view in elevation of a por-

tion of a bank counter to which the invention has been applied.

Fig. 2 is a horizontal sectional view taken on the line 2—2 in Fig. 1.

Fig. 3 is a vertical sectional view taken on the line 3—3 in Fig. 1.

Fig. 4 is a bottom plan view.

Fig. 5 is a sectional end elevation taken substantially on the line 5—5 in Fig. 1.

Fig. 6 is a detail view of the circuit making and breaking mechanism.

Corresponding parts in the several figures are denoted by like characters of reference.

The counter 15 is supported by uprights 16 rising from a platform 17 which is supported above the floor 18. The uprights 16, or 70 the portions of said uprights lying between the platform 17 and the floor 18 are provided with slots 19 to accommodate and to permit the vertical movement of the bridge portion 20 of a yoke. The limbs 21 of the 75 yoke are guided for vertical movement in keepers 22 on the uprights 16.

The uprights 16, in addition to supporting the customary grille 23, afford bearings for a shaft 24 which serves as a drum to which 80 a curtain 25 is attached and on which said curtain may be wound. The curtain is provided at the free edge thereof with a heavy bar 26 the tendency of which is to gravitationally unroll the curtain, said bar being 85 guided in grooves 27 in the inner faces of the uprights 16. The shaft 24 is provided at the ends thereof with spur wheels 28 which are adapted to be engaged by dogs 29 formed at the upper ends of the limbs 21 of 90 the yoke previously referred to.

The bridge piece 20 of the yoke having the limbs 21 is normally forced in an upward direction by the action of springs 30 which are socketed in the lower ends of the 95 uprights 16. The said bridge piece 20 is provided with an arm 31 which lies in the path of a vertically movable pedal 32 that extends through the platform 17 in a convenient position to be touched or actuated by the foot of the cashier standing behind the counter. The arm 31 might be dispensed with, and the pedal 32 might be made to impinge directly on the bridge piece 20, but the arm 31 provides a greater area for engagement with the pedal member 32 and tends to insure certainty of operation. 33 designates an electrical battery in the circuit

of which is included a bell or sounder 34. The conductors 35 include a simple device for making and breaking the circuit, the same having been shown as comprising a 5 pair of springs 36, normally engaging an insulating strip 37 on one of the limbs 21 but which, when the limb 21 carrying said insulating strip is lowered, will engage each other, thus completing the circuit and causing 10 the bell 34 to be sounded. When the limb 21 carrying the insulating strip 37 is lifted, to its normal position, the springs 36 will be forced apart, and the circuit will be broken, causing the sounding of the bell to 15 be interrupted.

Fixed on the underside of the platform 17 is a resilient dog 38 on which the bridge member 20 is normally supported, said dog having a depending lip 39 provided with 20 a recess 40 in which the bridge member 20 is received when said bridge member is depressed by the action of the pedal 32. This device serves to retain the yoke comprising the bridge member 20 and the limbs 21 to 25 be retained in a depressed condition against the tension of the springs 30. The resilient dog 38 however, lies in the path of a pedal member 41 which extends through the platform 17 and by the action of which the said 30 resilient dog may be forcibly depressed to disengage the same from the bridge member 20. When the dog 38 is thus depressed the bridge member will be released and the yoke of which it forms a portion, will be raised 35 by the springs 30 to its initial or normal position.

In the operation of this device it will be understood that the curtain is normally wound on the shaft 24 which forms a drum 40 or roller for said curtain. The curtain is normally retained in such wound condition by the engagement of the dogs 29 at the upper ends of the limbs 21 with the spur wheels 28. By pressing the pedal 32 the 45 cashier standing behind the counter may disengage the dogs 29 from the spur wheels 28, causing the curtain to be swiftly unrolled by the gravity of the bar 26 which is guided in the grooves 27. At the same time, the 50 depression of the limbs 21 will move the insulating strip 37 from its position between

the springs 36, thereby causing the making of the circuit including the alarm bell 34 which may be located at any desired point, either close or distant. The depression of 55 the bridge piece 20 causes the same to be received in the recess 40 in the lip 39 of the resilient dog 38 where it will be retained against the tension of the springs 30. By depressing the pedal 41 the cashier or operator may disengage the bridge piece 20 permitting the latter and the limbs 21 connected therewith, to be lifted by the action of the springs 30 thereby interposing the insulating strip 37 between the springs 36, 65 thus breaking the circuit and interrupting the sounding of the alarm.

I claim:—

1. In a device of the class described, a pair of uprights, a roller supported for rotation in said uprights and having spur wheels at the ends thereof, a curtain wound on said roller and having a bar whereby it may be gravitationally unrolled, a yoke having limbs guided on the uprights and provided with dogs engaging the spur wheels, springs supporting the yoke and maintaining the dogs normally in engagement with the spur wheels, and means whereby said yoke may be depressed against the tension 80 of the springs.

2. In a device of the class described, a pair of uprights, a roller supported for rotation in said uprights and having spur wheels at the ends thereof, a curtain wound 85 on said roller and having a bar whereby it may be gravitationally unrolled, a yoke having limbs guided on the uprights and provided with dogs engaging the spur wheels, springs supporting the yoke and maintaining the dogs normally in engagement with the spur wheels, and means whereby said yoke may be depressed against the tension of the springs; in combination with a resilient dog having a lip provided 90 with a recess adapted to receive the bridge member on the yoke to maintain the latter in depressed position against the tension of its actuating springs.

In testimony whereof I affix my signature. 100

CHARLES M. SEARS.
